Joshua Tracy

UNITED STATES PATENT OFFICE.

HENRY HALCROFT, OF MEDIA, ASSIGNOR OF ONE-HALF OF HIS RIGHT TO
LEWIS PALMER, OF CONCORDVILLE, PENNSYLVANIA.

SHEDDING MECHANISM FOR LOOMS.

SPECIFICATION forming part of Letters Patent No. 228,191, dated June 1, 1880.

Application filed January 5, 1880.

To all whom it may concern:

Be it known that I, HENRY HALCROFT, of Media, in the county of Delaware and State of Pennsylvania, have invented a new and useful Improvement in Shedding Mechanisms for Looms, of which the following is a specification, reference being had to the accompanying drawings.

My invention relates particularly to those looms having rollers above and treadles below the heddles, whereby the latter are vibrated, and specifically to an improved mode and devices for connecting the heddles with the treadles, whereby the connecting straps or cords are made more nicely and readily adjustable than heretofore, each independently of the others, and also whereby a considerable saving in wear and tear is effected, as herein-after explained.

Figure 1 of the accompanying drawings is a longitudinal section of a loom to which my improvement has been applied. Fig. 2 is a front view of the same; and Fig. 3 is a vertical sectional view of one form of my invention, as hereinafter described.

H are the heddles; J, the heddle-jacks; T, the treadles; C, cords or straps connecting the jacks and heddles; E, cams or tappets which operate the treadles; P, a plate with openings to receive screw-pins S.

F is the frame of the loom.

This being an ordinary roller-loom, I shall refer only to those parts necessary to a clear understanding of my improvement.

In the roller-looms in general use the connection between the heddle-jack and treadle is made by means of a common flat leather strap, with holes, attached to the jack and passed down around a sheave or hook fixed to the treadle, then up and buckled. Being a practical weaver, I have noted the defects of this plan, which my invention is intended to obviate to a greater or less degree. These are, first, by reason of the constant vibration and consequent friction when the loom is in motion, the straps and buckles wear out comparatively soon, and also sometimes become unbuckled; second, the adjustment of the length of the straps whereby the shed may be altered can neither be nicely nor readily made; third, the

loom must be stopped in order to unbuckle and draw up or let out the straps, as may be desired.

In a common four-treadle loom like that shown in the drawings there are sixteen straps, 55 or, more accurately, eight doublings, between the jacks and treadles, whereas my improvement employs but one-half the number, or eight single straps.

Each of the cords C is attached to jacks J 60 and passes through eyes or around sheaves on the treadle T, (there being in this instance two eyes or sheaves to each treadle,) and thence to a screw pin or bolt, S, to which it is fastened, as shown. Each pin S projects through an 65 opening in a plate, P, which is screwed or nailed to frame F. After the cord is attached to pin S the connection between the heddle-jack and treadle may be practically lengthened or shortened, thereby altering the shed, 70 by turning the nut N, and it is evident that this may be done readily and to a nicety without stopping the loom.

It is also plain that other equivalent adjusting devices arranged substantially as that I 75 have described may be substituted—for instance, that shown by Fig. 3, wherein the ordinary flat strap C', with its series of holes x, is fastened to the heddle-jack J', passed down around sheave e', and its free end caught by 80 passing one of the pins or studs S', projecting from plate P', through any one of the perforations x, provided for the purpose; or the holes may be dispensed with and a suitable clamping device be employed to hold the strap at 85 the desired point.

I claim—

In combination with cords C, the heddles H, and the treadles T, provided with eyes or sheaves, the plate P, provided with a series of 90 screw-pins and nuts, or equivalent devices, for securing the free ends of the cords, each independently of the others, whereby any one of said cords may be readily let out or drawn up while the loom is in motion, substantially as 95 described.

HENRY HALCROFT.
